UNITED STATES PATENT OFFICE.

GUY H. ELMORE, OF SWARTHMORE, PENNSYLVANIA.

CENTRIFUGAL DRIER.

1,334,023.

Specification of Letters Patent. Patented Mar. 16, 1920.

Application filed October 7, 1916. Serial No. 124,348.

To all whom it may concern:

Be it known that I, GUY H. ELMORE, a citizen of the United States, residing at Swarthmore, in the county of Delaware and 5 State of Pennsylvania, have invented certain new and useful Improvements in Centrifugal Driers, of which the following is a specification.

This invention relates to continuous centrifugal driers intended for handling granular material and particularly to special 10 mechanical features which render the device self-clearing and permit continuous operation even when handling materials which 15 tend to cake on and clog the screen element of the drier.

The invention involves features described and claimed in my Patent No. 1,235,193, July 31, 1917, which resulted from a co- 20 pending application, Serial No. 718,931, filed September 6, 1912, and these accordingly are not claimed herein.

Generally stated the present invention involves a downwardly flaring conical screen 25 mounted to rotate upon a vertical axis, the flare or angle of the conical screen being so chosen that with the material handled and at the speed chosen for operation the centrifugal feeding tendency will not be quite 30 sufficient to effect a feeding of the material down the screen. In conjunction with this rotating screen I use a coaxial rotating conveyer having substantially helical flights of relatively quick pitch, the conveyer rotating 35 at a slightly different, and preferably at a slightly slower speed than the screen. The difference in speed and the pitch of the flights are chosen so as to feed the material down the conical screen at such speed that 40 it will be dewatered to the desired degree by the time it is discharged from the lower end of the conical screen. By proper design a condition may be realized at which 45 the conveyer need exert only a slight feeding tendency on the granular material to secure the desired action and consequently the conveyer blades may be given a very quick pitch and the difference of speed of the conveyer and screen may be accordingly relatively slight so that the wear is reduced to a 50 minimum.

The above features are characteristic of the structure described and claimed in my

prior application above identified. It has been found, however, that in handling certain materials usually those of a fine granular texture, such as crystalline salts, there is a tendency for the screen ultimately to clog, requiring stopping of the machine and cleaning of the screen. There is necessarily a clearance allowed between the conveyer 55 blades and the screen and this leads to the formation of a film or layer of granular material which remains on the screen and does not move forward with the bulk of the 60 material handled by the drier. The formation of this layer is beneficial because it serves as a sort of filter bed, preventing the finer particles from passing through the 65 meshes of the screen as they would otherwise do. In time, however, this layer becomes substantially impervious to water, 70 hindering the action of the drier, and it is desirable periodically to remove this film or layer and thereafter allow a new one to 75 form. The purpose of my invention is to accomplish this effect automatically and without requiring the stopping of the drier and 80 without interrupting its continuous action.

The means utilized for this purpose is a mechanism which reduces the clearance periodically and temporarily between the conveyer blades and the screen. As the simplest mode of effecting this result I have adopted a relative axial movement of the 85 screen and conveyer elements which is automatically effected at set periods during the operation of the machine. Either the screen element or the conveyer element or both might be shifted but as the simplest and 90 most satisfactory method I prefer that of shifting the conveyer element and a machine embodying this particular arrangement is illustrated in the accompanying 95 drawings, in which:

Figure 1 is a vertical axial section of such a machine;

Fig. 2 is a section on the line 2—2 of Fig. 1;

Fig. 3 is a fragmentary view showing the 100 screen structure in section with a part of the interior screening element broken away the conveyer element being shown partly in section and partly in elevation, a portion of the same being also broken away to give a 105 clearer view of the screen;

Fig. 4 is a section on the line 4—4 of Fig. 1;

Fig. 5 is a fragmentary elevation looking at the right hand side of the machine 5 with reference to Fig. 1;

Fig. 6 is a section on the line 6—6 of Fig. 1; and

Fig. 7 is an enlarged view showing the bearing and bearing adjusting mechanism 10 for the quill shaft which carries the conveyer element.

The entire machine is supported in a combined frame and hopper structure which comprises a base plate 11, an interior shell 15 12 and an exterior shell 13, the annular space between the shells 12 and 13 being the discharge hopper for the dried material leaving the machine. The annular space between these two shells is not continuous except at the top adjacent the point of discharge from the screen as it is necessary to form openings through the shells at opposite sides of the machine to permit access to the drive mechanism. Consequently 20 25 steep inclined webs or partitions 14 extending between the shells 12 and 13 are provided to direct the dried granular material to the two discharge openings 15 which lead through the base plate 11. The frame thus forms two funnel like portions which will direct the dry granular material to the discharge openings and prevent banking or accumulation of the dried material.

The upper end of the shell 12 curves inwardly at 16 to form a guard flange intended to prevent any material from entering the machinery space inside the shell 12. The flange 16 extends upward within the conveyer rotor shell far enough to secure this 30 35 result. The shell 13 carries at its upper end an exterior trough or launder 17 having water discharge openings 18 designed to convey away water and other liquids which may be extracted by the drier. The outer 40 45 wall of the launder 17 is provided with internal lugs 19 to support a removable conical guard shell 20, which incases the screen and deflects the water passing through the screen downward into the launder 17.

50 Mounted directly on the base plate 11 is a bearing plate 21 which carries a ball thrust bearing 22 and a ball journal bearing 23 for a vertical shaft 24 which is driven through the belt pulley 25. This is the main 55 drive shaft of the machine and carries the screen. Extending across the frame structure of the machine and removably bolted to the shell 12 near the top thereof is a cross frame 26 in which is threaded an adjusting 60 65 nut or slideway 27. Mounted to slide vertically in this slideway is a sleeve bearing 28 which carries a ball thrust bearing 29. Turning in the sleeve bearing 28 is the quill shaft 30 within which turns the shaft 24. 65 The quill shaft 30 carries at its upper end

the bell shaped conveyer shell 31 which is locked against a shoulder on the sleeve 30 by means of a nut 32, the nut 32 being split and provided with a clamp screw 33 to prevent its backing off. The hub portion 34 of 70 the conveyer element 31 rests upon the ball thrust bearing 29. Since the sleeve bearing 28 is axially slidable within the nut 27 it will, when lifted by suitable mechanism hereafter described, lift the conveyer shell 31 and the connected quill shaft 30, through the interposed ball thrust bearing 29. The lowermost position assumed by the sleeve bearing 28, and consequently by the quill shaft and the conveyer element, may be adjusted by adjusting the nut or slideway 27. Thus the sleeve bearing 28 not only guides the shaft 24 and the quill shaft 30 in their 75 80 rotary movements, but also guides the quill shaft in its vertical or axial movements relative to shaft 24, and is the medium through which the lifting or shifting force is applied. This shaft 24 carries at its upper end the spider or frame for the screen element. This spider comprises a hub portion 85 90 95 35 held against a shoulder on the shaft 24 by means of a suitable nut and washer 36; a series of radial spokes 37 which are so formed as to comprise helical conveyer blades; an upwardly extending annular rim 38 forming a receiving hopper and a downwardly flaring conical grating structure consisting of the elemental bars 39 and annular flanges 40 which connect the same. The lower edge of the screen spider takes the 100 105 form of a grooved water guard ring 41 which straddles the upper edge of the shell 13 and keeps separate the dried granular material and the water separated therefrom as the two are discharged respectively from within and without the screen.

The screen proper consists of perforated plates or other suitable foraminous material 42 applied in sections to the interior of the spider and retained therein by tapered locking bars 43 which are drawn by bolts 44 into grooves formed on the interior of the spider. These grooves are preferably formed in enlarged bars 45 similar to the bars 39 which occur at regular intervals. The edges of 115 the foraminous material are bent into the aforesaid grooves at either side of the bars 43, and are clamped therein by setting up the nuts 44 as will be apparent upon an inspection of Figs. 2 and 3. The bell shaped shell 31 of the conveyer element is mounted within the screen structure just described and has a flare or taper conforming to that of the screen. The shell extends downward to the upper extremities of the flanges 16 described as formed on the upper end of the shell 12 and is provided on its outer face with a plurality of quick pitch helical conveyer flights which turn in close proximity 120 125 to the interior surface of the screen, only 130

sufficient clearance being allowed to permit the formation of the desired film of granular material heretofore mentioned.

A cross frame 46 is provided extending 5 across the interior of the shell 12 and having a bearing 47 for the shaft 24. A bracket 48 is removably bolted to the cross frame 46 and carries a fixed journal pin 49 whose upper end is supported at 50 in the cross 10 frame 26. A sleeve 51 is journaled on the pin 49, and rests against a ball thrust bearing 52 interposed between it and the top of the bracket 48. A grease cup 53 communicating with ducts 54 in the journal pin is 15 provided to lubricate the sleeve 51. A pair of gears 55, 56 of slightly different sizes are fast on the sleeve 51, the gear 55 meshing with a companion gear 57 fast on the quill shaft 30, and the gear 56 meshing with a 20 companion gear 58 fast on the main shaft 24. The ratio of the gears is such that the quill shaft 30 is driven through the gear train by the shaft 24 at a slightly lower angular velocity. The bearing between the 25 shaft 24 and quill shaft 30 is lubricated by means of a grease cup 59 which is covered by a removable cap 60 and communicates with suitable ducts 61 in the shaft 24. Oil will be continually supplied to the thrust 30 bearing 29 and the sleeve bearing 28 by means of a pipe 62, which dips into an annular trough 63, formed in the upper face of the gear 57, pressure to lift the oil being supplied by the centrifugal tendency of the 35 oil in the trough 63. A groove 64 is formed at the lower end of the sleeve bearing 28 to catch any excess oil that may flow down the bearing and feed it by means of a pipe 65 (see Fig. 7) to the trough 63.

40 The structure so far described is available for use as a drier where the self-clearing action is not essential.

The mechanism for lifting the sleeve 28 and consequently the conveyer element to 45 reduce the clearance between the latter and the blades of the screen in order to cause the clearing of the screen will now be described.

Fast on the shaft 24 is a worm 66 which 50 meshes with a worm wheel 67. The worm wheel 67 is fast on a shaft 68 which turns in bearings 69 on the cross frame 46. The frame 46 is formed with an oil retaining recess 70, in which the worm and wheel run 55 so that these are thoroughly lubricated. The shaft 68 is also supported by a bearing 71 carried on the shell 12 and carries at its outer end a radially slotted crank 72. A crank pin 73 is provided and this may 60 be clamped in any desired radial adjustment in the slot of the crank 72 so as to adjust the throw thereof. The crank pin 73 is connected by a short connecting rod 74 (which is made adjustable in length by 65 means of a turnbuckle) to the vertical arm

75 of a bell crank whose other arm 76 carries a roller pawl 77. This pawl 77 contacts with the periphery of a disk 78 so that as the machine is driven the disk 78 will be intermittently rotated in one direction. The 70 disk 78 is fast on a shaft 79 mounted in suitable fixed bearings 80 and carrying a worm 81, which in turn drives a worm wheel 82 fast on shaft 83. This shaft turns in the fixed bearings 84. The shaft 83 carries 75 a cam 85 having a radial projection or finger 86. The cam 85 bears against a roller 87 on the vertical depending bifurcated arm 88 of a bell crank whose two horizontal arms 89 extend beneath and bear against the 80 sleeve bearing 28. Thus as the machine is driven the cam 85 is slowly and intermittently rotated and when the finger 86 engages the roller 87 it will force the same to the left as viewed in Fig. 1, thus lifting 85 the sleeve bearing 28 and with it the quill shaft 30 and conveyer shell 31 so that the conveyer flights will move virtually into contact with the inner face of the screen and clear the same of the accumulated layer 90 of granular material forcing such material to discharge from the machine. Thereafter the passage of the finger 86 past the roller 87 will allow the conveyer rotor to sink back to its original position restoring the original 95 clearance between the conveyer blades and the screen. The amount of this normal clearance is adjusted by adjusting the nut 27. In order to permit a corresponding adjustment of the bell crank 88, 89, this is 100 journaled on a shaft 90, whose ends are mounted in slide blocks 91. These are mounted in vertical guide-ways 92 and may be adjusted vertically therein by means of adjusting screws 93. A considerable range 105 of adjustment of the frequency of the clearing action may be had by adjusting the throw of crank pin 73, an adjustment of the length of the connecting rod 74 being made if necessary to preserve the proper position 110 of the ratchet bell crank structure 75, 76.

The operation of the device will be readily understood from the above description. Briefly the characteristic operation of the machine is:

115 The granular material fed to the rotating hopper at the top of the machine will be urged downward by the conveyer blades 37, and will be quickly thrown by centrifugal force against the screen. The centrifugal 120 tendency of the material is not sufficient to feed it down the screen but this feeding is brought about by the inclined conveyer blades carried by the conveyer rotor which is turning at slightly less speed. The moisture contained in the material will be thrown through the screen and deflected by the cover 20 into the launder 17 from which it will flow to waste. The dried granular material upon leaving the screen will flow 130

downward between the shells 12 and 13 and will be discharged to any suitable container through the openings 15. During the major portion of the operation of the device there will be sufficient clearance between the conveyer blades of the screen to permit the existence of a layer or bed of granular material to serve as a sort of filter, but this bed will be periodically removed by the rising of the conveyer element. In this way clogging and blinding of the screen are prevented and continuous operation is secured.

The construction above described has certain practical advantages of accessibility and easy adjustment. The exterior portion of the screen is exposed by merely removing the cover 20. The removal of the oil cap and a single nut permits the removal of the entire screen structure for replacement or repair, and this exposes the entire exterior portion of the conveyer rotor. The conveyer rotor may be lifted out, together with the quill shaft, by the mere releasing of the gear 57 which is held by a single nut, as clearly indicated in Figs. 1 and 3.

The shifting mechanism is all accessible for adjustment or repair without dismantling the machine as the bearings for this mechanism are readily dismounted. The shifting mechanism is mounted in what would otherwise be waste space in the drier, so that the size of the machine is not increased by the addition of this mechanism. In driers for handling material which has no tendency to cake upon the screen the entire shifting mechanism may be omitted, no other change being required.

Having thus described my invention, what I claim is:—

40 1. In a centrifugal drier, the combination of a rotatable annular screen; a conveyer element mounted to rotate coaxially with said screen within the same and having scrapers or flights moving near to but out 105 of contact with said screen; and an automatic mechanism operating periodically to reduce the clearance between said screen and flights to effect a clearing of the screen.

2. In a centrifugal drier, the combination of a rotatable screen; a conveyer element provided with helical flights mounted to rotate coaxially with said screen to feed material along the same; and automatic mechanism for moving said conveyer to reduce temporarily the clearance between it and the screen to cause clearing of the screen.

3. The combination of a flaring rotary screen; a conveyer element mounted to rotate coaxially within said screen to convey material along the same; and means for periodically producing a relative axial movement of said screen and conveyer to reduce the clearance between the same.

65 4. The combination of a conical rotary

screen; a conveyer element mounted to rotate coaxially within said screen to convey material along the same; and means for periodically producing a relative axial movement of said screen and conveyer to reduce 70 the clearance between the same.

5. The combination of a substantially conical rotary screen; a conveyer element mounted to rotate coaxially therewith and provided with substantially helical flights; 75 means for driving said screen and conveyer element in the same direction at slightly different speeds; and a mechanism for producing a relative axial shifting movement between the screen and conveyer to periodically and temporarily reduce the clearance 80 between the same.

6. The combination of a substantially conical rotary screen; a conveyer element of the spiral type mounted to rotate coaxially within the same; and a driving mechanism adapted to rotate said screen and conveyer in the said direction at different speeds and periodically to produce a relative shifting motion between the conveyer and 90 screen to change the clearance between the same.

7. In a rotary drier the combination of a flaring annular rotary screen; a rotary conveyer mounted coaxially within the same 95 and spaced from the screen to permit the formation of a layer of the material being dried; and means for periodically causing said conveyer to remove and discharge said layer during the normal operation of the 100 machine.

8. In a centrifugal drier, the combination of a rotary shaft; a substantially conical screen carried thereby; a quill shaft journaled on said shaft; a conveyer element having spiral flights carried by said quill shaft; and an actuating mechanism for rotating said shafts in the same direction at unequal speeds and periodically shifting said quill shaft axially to temporarily reduce the 110 clearance between said conveyer element and screen.

9. In a centrifugal drier, the combination of a rotary shaft; a substantially conical screen carried thereby; a quill shaft journaled on said shaft; a conveyer element having spiral flights carried by said quill shaft; an actuating mechanism for rotating said shafts in the same direction at unequal speeds and periodically shifting said quill 120 shaft axially to temporarily reduce the clearance between said conveyer element and screen; and means to vary the frequency of the periodic shifting action.

10. In a centrifugal drier, the combination of a rotary shaft; a substantially conical screen carried thereby; a quill shaft journaled on said shaft; a conveyer element having spiral flights carried by said quill shaft; a gear train interposed between said 125

130

shafts to constrain them to rotation in the same direction at unequal speeds; and a shifter mechanism driven from one of said shafts and operatively related to both shafts 5 to periodically cause a relative axial shifting movement of said shafts to reduce temporarily the clearance between the conveyer and screen.

11. In a centrifugal drier, the combination of a rotary shaft; a substantially conical screen carried thereby; a quill shaft journaled on said shaft; a conveyer element having spiral flights carried by said quill shaft; a gear train interposed between said 15 shafts to constrain them to rotation in the same direction at unequal speeds; a shifter mechanism driven from one of said shafts and operatively related to both shafts to periodically cause a relative axial shifting 20 movement of said shafts to reduce temporarily the clearance between the conveyer and screen; and a change speed mechanism interposed in the drive to said shifter mechanism to vary the frequency of its 25 action.

12. In a centrifugal drier the combination of a flaring rotary screen; a conveyer element mounted to rotate coaxially within said screen to convey material along the 30 same; a frame for supporting said screen and conveyer element; two thrust bearings mounted in said frame, one of said bearings supporting said screen and the other of said 35 bearings supporting said conveyer element; and means for adjusting one of said thrust bearings in said frame to adjust the clearance between said screen and conveyer element.

13. In a centrifugal drier, the combination of a flaring rotary screen; a conveyer element mounted to rotate coaxially within

said screen to convey material along the same; step bearings independently supporting said screen and conveyer element; a support in which one of said bearings is slidably mounted; and adjustable means for limiting the sliding movement of said bearing in said support whereby the maximum clearance between said screen and conveyer 45 element may be limited.

14. In a centrifugal drier, the combination of a flaring rotary screen; a conveyer element mounted to rotate coaxially within said screen to convey material along the same; adjustable means for limiting the 50 axial separating movement of said screen and conveyer; and an automatic shifter mechanism operating periodically to reduce the clearance between said conveyer and screen by a relative axial shifting movement 55 of the two.

15. In a centrifugal drier, the combination of a substantially cylindrical frame structure forming an annular discharge chute for the dried material; a conical screen 60 rotatably mounted on said frame structure above the same and adapted to discharge into said discharge chute; a rotary conveyer element mounted coaxially within said screen; a driving mechanism for driving 65 said screen and conveyer in the same direction at unequal speeds; and a shifting mechanism adapted to effect a periodic axial shifting movement of the screen and conveyer to vary the clearance between the 70 same, said driving and shifting mechanisms being mounted wholly within the cylindrical portion of said frame structure.

In testimony whereof I have signed my name to this specification.

GUY H. ELMORE.
